UNITED STATES PATENT OFFICE.

HUGH DAVIS, OF MELVIN, MICHIGAN.

DIRT-MACHINE.

1,206,819.

Specification of Letters Patent. Patented Dec. 5, 1916.

Application filed April 9, 1915. Serial No. 20,109.

To all whom it may concern:

Be it known that I, HUGH DAVIS, a citizen of the United States of America, residing at Melvin, in the county of Sanilac and State of Michigan, have invented certain new and useful Improvements in Dirt-Machines, of which the following is a specification, reference being had therein to the accompanying drawings.

10 This invention relates to a dirt machine that can be advantageously used for scraping and collecting dirt, rubbish or refuse matter upon a street or for scraping and collecting dirt from a roadbed or road where-
15 by the dirt can be used for grading or filling in purposes.

A dirt machine in accordance with my invention embodies a main frame and running gear, a rotary sweeper brush and adjustable 20 scrapers for placing matter in the path of the brush, an adjustable collecting chute and conveyer casing, an endless conveyer and its operating mechanism, and a controlling device for the endless conveyer, all of these 25 mechanisms and devices being assembled in the form of a rigid and durable vehicle. In the general make up of the dirt machine, the parts are constructed with a view of reducing the cost of manufacture and at the 30 same time retaining the features by which safety, simplicity, and ease of manipulation is secured, and with such ends in view, my invention resides in the novel construction, combination and arrangement of parts to be 35 hereinafter specifically described and then claimed.

Reference will now be had to the drawings, wherein—

Figure 1 is a longitudinal sectional view of 40 a dirt machine in accordance with this invention; Fig. 2 is a plan of the same partly broken away and partly in section, and Fig. 3 is a cross sectional view of the machine looking toward the rear end thereof.

45 In describing my invention by aid of the views above referred to, I desire to point out that the same are intended as merely illustrative of an example whereby my invention may be applied in practice, and I 50 do not care to confine my invention to the precise construction and arrangement of parts shown. The following description is therefore to be broadly construed as including substitute constructions and arrangements of parts which are the obvious equivalents of those to be hereinafter referred to.

In the drawings, 1 denotes parallel channel side frames having the ends thereof connected by transverse channel bars 2 and 3 braced relative to the side frames 1 by top 60 and bottom corner pieces 4.

5 denotes a bolster at the forward end of the main frame and this bolster is provided with a conventional form of fifth wheel 6 supported by an axle 7 having wheels 8 and 65 a draft equalizer 9 by which the dirt machine is towed or connected to the rear end of a wagon or other vehicle.

10 denotes depending bearings at the rear end of the main frame for a revoluble axle 70 11 and mounted upon the ends of said axle are traction wheels 12. Contiguous to the depending bearings 10 are the hubs 13 of sprocket wheels 14. The confronting ends of the hubs 13 constitute clutch members 75 adapted to be engaged by clutch members 15 slidably keyed upon the axle 11 and adapted to rotate therewith. The clutch members 15 have the confronting ends thereof provided with heads 16 and interposed between 80 said heads and encircling the axle is a coiled compression spring 17 which holds the clutch members 15 normally in engagement with the ends of the hubs 13. With the hubs 13 loose upon the axle 11, the clutch 85 members 15 are adapted to establish rotative continuity between the axle 11 and the hubs 13, and in order that the clutch members 15 can be retracted to permit of the dirt machine being moved without imparting movement to the hubs 13, a set of levers 18 are employed. The set of levers 18 is suspended from bearings 19, carried by a beam 23 mounted upon the frames 1 and connected thereto by angle brackets 24. The levers 18 95 are pivotally connected to toggles 20 which are pivotally connected to the lower end of a rod 21 slideable in a vertically disposed guide 22, carried by the transverse beam 23. The upper end of the rod 21 is pivotally 100 connected to a link 25 and said link is pivotally connected to a fulcrumed operating lever 26. The lever 26 is fulcrumed upon a tripod 27 supported by the beam 23 and the channel bar 3, and said tripod has 105 a segment rack 28 engaged by a conventional form of ratchet mechanism 29 carried by the operating lever 26. With the lower ends of the lever 18 bifurcated and spanning the clutch members 15 to engage the 110 heads 16 thereof, said levers can be shifted toward each other by operating the lever 26

to retract the clutch member 15 and thereby release the hubs 13 relative to the rear axle.

30 denotes depending bearings carried by the side frames 1, in proximity to bearings 5 10, and journaled in the bearings 30 is a transverse driven shaft 31 having the ends thereof provided with sprocket wheels 32. Trained over these wheels and the sprocket wheels 14 are endless sprocket chains 33, 10 whereby the shaft 31 will be driven from the rear axle 11. Loosely upon the shaft 31 are the side walls 34 of an inclined scoop or chute 35, which has the forward end thereof open and the rear end provided with a 15 curved and upwardly directed deflector 36. The side walls 34 of the scoop are secured to side frames 37 loose upon the shaft 31 and the rear ends of said side frames are connected by a yoke 38. Loosely connected 20 to the rear end of the yoke 38 is the lower end of a rod 39 which has a screwthreaded portion 40 in engagement with a bearing 41, carried by the channel bar 3. The upper end of the rod 39 has a suitable hand wheel 25 42 and by adjusting the rod 39 relative to the bearing 41, the rear end of the yoke 38 can be raised and lowered, thereby raising and lowering the forward open end of the scoop or chute 35.

30 43 denotes an operator's seat supported on the channel bar 3 and this seat is in proximity to the hand wheel and the operating lever 26.

44 denotes bearings carried by the forward ends of the side walls 34 of the scoop or chute 35 and journaled in said bearings is the spindle 45 of a rotary brush 46. One end of the brush 46 has the spindle thereof provided with a small sprocket wheel 47 35 40 longitudinally alining with a sprocket wheel 48 on the driven shaft 31. Trained over the sprocket wheels 47 and 48 is an endless sprocket chain 49, whereby a rotary movement will be imparted to the brush 46 when 45 the shaft 31 is driven from the rear axle 11 of the machine. The bristles of the brush 46 are in proximity to the front lower edge of the scoop or chute 35 and said brush is adapted to sweep dirt and other matter 50 into the scoop or chute as the machine is moved over a street or road.

50 denotes converging and angularly disposed scrapers at the sides of the main frame of the machine and at the front edges 55 of the walls 34 of the scoop or chute 35. These scrapers are carried by depending arms 51 of rock shafts 52 journaled in bearings 53, carried by the side frames 1 of the machine. The outer ends of the rock shafts 60 52 are provided with cranks 54 connected by reach rods 55 to cranks 56 of rock shafts 58, journaled in bearings 57 supported by the main frame of the machine. Some of the bearings 57 are in the form of racks 65 or notched plates and adjacent to these bear-

ings are operating levers 59 fixed to the rock shafts 58 whereby said shafts can be easily rocked. The operating levers 59 have pawl mechanisms 60 of the ordinary and well known type whereby said operating levers 70 can be locked in an adjusted position relative to the racks forming part of certain of the bearings 57. By reference to Fig. 1, it will be observed that the operating levers 75 59 are conveniently located to be manipulated by an operator upon the seat 43. By shifting the operating levers 59 the scrapers 50 can be tilted to avoid obstructions or to scrape a desired surface; the rear ends of the scrapers being rounded to permit of a 80 tilting movement.

61 denotes inwardly projecting brackets carried by the frame 1 contiguous to the depending bearings 3. The brackets 61 support the lower end of an inclined conveyer 85 guide 62, said conveyer guide extending forwardly and upwardly and forming the bottom of a conveyer casing 63. In addition to the brackets 61 there are inwardly projecting brackets 64 supporting the conveyer 90 guide 62 from a rigid inclined frame 65 supported by each of the side frames 1, the frames 65 having the forward ends thereof connected by a transverse channel bar 66. The conveyer casing 63 has the lower end 95 thereof in communication with the scoop or chute 35 and the top of said casing has a hinged door 67 whereby the access can be had to the interior of the casing 63. The upper end of the conveyer casing 63 terminates in a discharge spout 68 and this spout is adapted to deliver dirt or other material to a wagon to which the dirt machine is attached.

69 denotes a large sprocket wheel mounted 105 upon the driven shaft 31, at the inner sides of the wall 34 of the scoop or chute 35. These sprocket wheels 69 and 70 are endless sprocket wheels 70 mounted upon the shaft 71 journaled in adjustable bearings 72, carried by the upper ends of the frames 65. On these sprocket wheels 69 and 70 are endless sprocket chains 73 connected by spaced transverse angle bars 74, said angle bars and the sprocket chains constituting an endless 110 conveyer in conjunction with the casing 63. The endless conveyer within the scoop or chute 35 is braced and guided by a curved plate 75 connected to the lower end of the guide 62 and to the inwardly projecting 115 brackets 61 by straps 76 and a transverse bar 77. The angle bars 74 of the endless conveyer move in proximity to the bottom of the scoop or chute 35 and dirt or other matter brushed into the scoop is impinged 120 by the angle bars and conveyed upwardly against the deflector 36 of the scoop into the casing 63, where the endless conveyer gradually carries the dirt to the top of the conveyer casing and discharges the same into 125 130

the spout 68. With the clutch members 15 in engagement with the hubs 13 and the dirt machine towed over a surface, the brush 46 and the endless conveyer are driven to collect dirt or other matter and convey the same to the discharge spout 68. It is during the operation of the endless conveyer and the brush that the scoop or chute 35 can be adjusted through the medium of the hand wheel 42, the scrapers 50 adjusted through the medium of the operating levers 59, and the operation of the endless conveyer and brush controlled through the medium of the operating lever 26.

15 It is to be noted that throughout the construction of the dirt machine structural steel, such as channel and angle bars, together with I-beams, angle brackets and irons, have been used to provide a rigid and durable structure that will withstand considerable wear and tear, particularly when used as a road machine.

What I claim is:—

1. In a dirt machine, a main frame, a seat at the rear end of said frame, a bearing at the rear end of said frame, a driven shaft supported by said frame, a scoop supported by said driven shaft, rearwardly extending frames secured to said scoop and loose on said shaft, a yoke connecting said frames and extending below the bearing of said

frames, a conveyer casing in communication with said scoop, an endless conveyer movable in said casing and said scoop and driven by said shaft, and a rod connected by said yoke 35 in screwthreaded engagement with said bearing and extending upwardly in front of said seat.

2. In a dirt machine, a main frame, a seat support at the rear end of said frame, a single bearing on the rear end of said frame at the base of said seat support, a driven shaft supported by said main frame, a scoop supported by said driven shaft, rearwardly extending triangular shaped frames secured to the sides of said scoop loose on said shaft, a yoke connecting said frames and extending below the bearing on said frame, a conveyer casing in communication with said scoop, an endless conveyer movable in 50 said casing and said scoop and driven by said shaft, and a vertically disposed rod rotatably connected to said yoke in screwthreaded engagement with said bearing and extending upwardly in front of said seat.

In testimony whereof I affix my signature in presence of two witnesses.

HUGH DAVIS.
